UNITED STATES PATENT OFFICE

DAVID ANTHONY JOSEPH THOMAS, OF BOSTON, MASSACHUSETTS

CHANGEABLE EXHIBITOR

Application filed October 12, 1928. Serial No. 312,175.

This invention relates to new and useful improvements in changeable exhibitors, and aims to provide an exhibitor constructed as to employ natural or artificial light emanating 5 from any source not associated with the exhibitor in illuminating a traveling advertisement carrying strip provided as an essential element of the exhibitor. Generally the invention has to do with what is now known as 10 "day light signs". That is signs that include generally an advertisement carrying panel illuminated by the sun light or by the lights within the street. The present device is however an improvement over this now well 15 known type of sign in that means is provided whereby the various advertisements slowly change for the obvious purpose of providing a sign wherein a plurality of words or various advertisements may be displayed. Furthermore, 20 the present device may be manufactured and marketed at low cost, and furthermore, the same may be operated at minimum expenditure.

With the foregoing and other objects in 25 view as the nature of the invention will be better understood, the same comprises the novel form, combination and arrangement of parts hereinafter more fully described, shown in the accompanying drawings and claimed.

30 In the drawings wherein like reference characters indicate corresponding parts throughout the several views:

Figure 1 is a front elevation of my changeable exhibitor.

35 Figure 2 is a vertical longitudinal cross section.

Figures 3 and 4 are vertical transverse cross sections taken substantially upon the lines 3-3 and 4-4 of Figure 2, and looking in the 40 direction of the arrows, and

Figure 5 is a fragmentary plan view of the endless advertisement carrying strip employed in association with the invention.

Now having particular reference to the 45 drawings, my novel exhibitor consists of a housing 5 of suitable construction and of any predetermined dimensions which depend of course upon the manner in which the exhibitor is to be used. This housing is open 50 at its top side and provided at said side with

a hinge door 6 within which is a transparent panel 7 either plain or colored to permit natural or artificial light rays to pass into the housing. The front wall of said housing is provided throughout the major portion of 55 its area with a transparent, preferably uncolored panel 8, while located longitudinally within the housing and at approximately forty five degree angle is a reflector panel 9. Mounted transversely within the housing and adjacent the four corners thereof are rotating rollers 11 trained around which is an endless strip of material 12 of any desired 60 formation carrying throughout its length transparent advertisement markings or indicia 13, as in Figures 1 and 5. At one edge of this endless strip 12 the same is formed with sprocket teeth receiving slots 14, while the adjacent end of one of the lowermost rollers 11 is equipped with a sprocket gear 15, 65 this roller being operatively geared or otherwise connected with a small electric motor 16 located within the housing 5, see Figures 2 and 4. Arranged at the inside of the housing 70 beneath the reflector panel 9 and rigidly secured to the opposite side walls of said housing are longitudinally extending opposed pairs of roller supporting bars 17-17, 18-18, the opposed bars 18-18 being arranged in 75 position above the other pair of opposed bars 17-17 as clearly illustrated in these two views. Opposed faces of these bars are provided with sockets 17' and 18' to receive the end pintles of transversely arranged endless strip guide rollers 17^a and 18^a. The said endless strip 12 is guided around these rollers 80 in the manner as indicated in Figure 2, these rollers obviously compensating for any slack within the endless strip, the rollers being, as is apparent, adjustable relative to one another.

It will of course be obvious that the advertising matter of the strip 12 will be visible through the glass panel 8 in the front wall of the housing, by reason of the data being projected onto the reflector 9, this being accomplished by the passage of light rays through the panel 7 onto the endless strip.

In view of the foregoing description when 85 considered in conjunction with the accom- 100

panying drawing it will be apparent that I have provided a novel, simple, useful and inexpensive changeable exhibitor that is well adapted for all the purposes heretofore designated, and even though I have herein shown and described the invention as consisting of certain detail structural elements it is nevertheless to be understood that some changes may be made therein without affecting the spirit and scope of the appended claims.

Having thus described the invention, what I claim as new and desire to secure by Letters Patent is:—

1. In an exhibitor of the class described, the combination of a housing having a glass within its upper and one of its side walls, a reflector located longitudinally within the housing, and at an approximate angle of 45°, endless tape rollers arranged within the housing adjacent the four corners thereof, one of said rollers adjacent one end thereof being equipped with a sprocket gear, an endless tape having advertising media formed therein and associated therewith, trained around said rollers, said endless tape having one marginal edge thereof provided with a plurality of spaced openings adapted to engage with the teeth of said gear, and means within the housing operatively associated with said one roller for rotating the same for causing the movement of the tape around said rollers.

2. In an exhibitor of the character described, the combination of a housing having a glass panel within its upper and one of its side walls, an angularly disposed reflector located within the housing and extending longitudinally thereof, endless tape rollers arranged within the housing adjacent the four corners thereof, one of said rollers being equipped with a gear, an endless tape having advertising media formed thereon trained around said rollers, the marginal edge of said endless tape being provided with a plurality of spaced openings adapted to engage the teeth of said gear, a pair of spaced idle rollers arranged beneath the reflector and over which said endless tape is trained, means for mounting said pair of idle rollers for adjustment with respect to one another for taking up slack in said tape, an electric motor within the housing, and means operatively connecting the motor with said one roller for causing the movement of the tape around said rollers.

3. In an exhibitor of the character described, the combination of a housing having a glass within its upper and one of its side walls, a reflector located longitudinally within the housing and at an approximate angle of forty-five degrees, endless tape rollers arranged within the housing adjacent the four corners thereof, an endless tape having advertising media thereon and trained around said rollers, means within the housing for

causing the movement of the tape around said rollers, a pair of spaced idle rollers arranged beneath the reflector and over which said endless tape is trained for taking up slack in said tape, supports for said last named rollers, and said supports being provided with spaced sockets adapted to receive the ends of said last mentioned rollers for rotatably supporting the same within the housing.

4. In an exhibitor of the class described, in combination, a housing having a glass within its upper and one of its side walls, a reflector located longitudinally within the housing and at an approximate angle of forty five degrees, a plurality of endless tape rollers arranged within said housing, an endless tape having advertising media arranged thereon adapted to move over said rollers, said rollers being arranged to provide an upper run longitudinally of the box intermediate the top of said box and said reflector, and means for mounting certain two of said rollers for relative adjustment toward or away from one another for taking up slack in said tape.

In testimony whereof I affix my signature.

DAVID ANTHONY JOSEPH THOMAS.
